BENZANTHRONES AND A PROCESS OF
PREPARING THEM

Heinrich Greune and Karl Schneider, Frankfort-on-the-Main-Hochst, Germany, assignors to General Aniline & Film Corporation, a corporation of Delaware

No Drawing. Application April 22, 1939, Serial No. 269,412. In Germany June 18, 1938

8 Claims. (Cl. 260—364)

The present invention relates to benzanthrones and to a process of preparing them.

By condensing a reduction product of the anthraquinone containing oxygen, for instance, anthrone or anthranol, with glycerol in strong sulfuric acid, there is obtained according to German Patent Specification No. 176,018 the benzanthrone which is of technical importance for the preparation of dyestuffs. It has hitherto not been ascertained whether in this reaction the

10 with, for instance, methylene acetone occurs likewise unequivocally, only in reversed order of succession. As final product of this reaction there is obtained the Bz-1-methylbenzanthrone and not the Bz-3-methylbenzanthrone. It results that the methyleneacetone is added at first at the double linkage to the anthrone and that this addition product forms, while water is split off and dehydrogenation occurs, the Bz-1-methylbenzanthrone:

anthrone (or the anthanol) reacts at first with the aldehyde group or with the double linkage of the acroleine primarily formed from the glycerol, since in both cases as final product of the reaction the benzanthrone is obtained and an intermediate product has not been isolated.

The reaction described in German patent specification No. 490,187 of 9-anthrone with cinnamaldehyde occurs unequivocally, since by this reaction cinnamylideneanthrone is obtained as intermediate product and Bz-1-phenylbenzanthrone as final product. In this case the aldehyde-group of the cinnamaldehyde reacts at first with the anthrone, water being split off and the cinnamylideneanthrone being formed, and from this intermediate product there is formed by the dehydrogenating effect of the strong sulfuric acid the Bz-1-phenylbenzanthrone, so that the course of the reaction takes place according to the following scheme:

The reaction described in German patent specification No. 488,608 of anthrone or anthanol

25 In view of these various possibilities of reaction of 9-anthrone or 9-anthanol with unsaturated aldehydes and ketones it was to be expected that by the reaction of alpha-beta-unsaturated alpha-halogenaldehydes in each case benzanthrones halogen-substituted in Bz-2-position would be obtained.

30 We have found that by condensing a 9-anthrone or 9-anthanol unsubstituted in at least one of its positions peri to the 10-position with an alpha-beta-unsaturated aldehyde of the following general formula

35 40 wherein R means hydrogen or an alkyl radical, in the presence of sulfuric acid, benzanthrones

are obtained, and, as a surprising fact the alpha-halogen atom of the aldehyde is split off, prob-

ably in the form of hypochlorous acid which serves as a suitable oxidizing agent for the dehydrogenation of the dihydrobenzanthrones formed as intermediate products. By using, for instance, alpha-chlorocrotonaldehyde there is obtained in the course of a smooth reaction the Bz-3-methylbenzanthrone. The reaction probably occurs according to the following scheme:

A behavior quite similar to that of the unsaturated aldehydes of the above formula is shown by the saturated aldehydes of the following formula

wherein R represents a member of the group consisting of hydrogen and alkyl and X represents a member of the group consisting of hydroxyl methoxyl and halogen, and the acetals of the aldehydes of both the formulae.

The benzanthrones thus obtained in most cases with a quantitative yield serve as intermediate products for the preparation of dye-stuffs.

According to the new process new benzanthrone derivatives are obtainable, for instance, Bz-3-methylbenzanthrone compounds containing one or more substituents as, for instance, hydroxy, methoxy, methyl, halogen or carboxy. As compared with known processes for the preparation of benzanthrone derivatives the process of the present invention has the advantages that a better yield is obtained, that organic solvents and oxidizing agents are not necessary in the reaction and that the latter can be carried out under mild conditions, for instance, at a low temperature of, for instance, between about 0° C. and room temperature and that products of good purity are obtained.

The following examples serve to illustrate the invention, but they are not intended to limit it thereto; the parts are by weight:

1. In the course of about half an hour 10.5 parts of alpha-chloro-crotonaldehyde are added, drop by drop, to an anthrone solution prepared by stirring for a prolonged time at room temperature 19.4 parts of anthrone and 300 parts of sulfuric acid of 80 per cent. strength. The solution assumes at once a red coloration and a test portion added to concentrated sulfuric acid shows an orange-yellow fluorescence. As soon as the reaction has fully set in streams of hydrogen chloride escape with vivid foaming. By vividly stirring for a prolonged time at room temperature the reaction is promoted. It may be brought to an end by stirring for about one hour at 70° C. The solution is poured on ice, while stirring, the crude product separates in the form of brown-yellow flakes. It is filtered

with suction, washed until neutral and dried. The yield of the crude product is quantitative and after recrystallizing the product from methanol or ethanol it amounts to 80 per cent. of the theory of the Bz-3-methylbenzanthrone melting at 113° C. to 114° C. It dissolves in concentrated sulfuric acid to an orange-red solution having an intense yellow-red fluorescence.

It is not necessary that in this process solid anthrone is used, but the alpha-chloro-crotonaldehyde may also be added, drop by drop, to an anthrone solution prepared, for instance, by reduction of anthraquinone with a metal powder in sulfuric acid solution according to German patent specification No. 201,542, whereby the same result is obtained.

2. By using in the process of this example instead of alpha-chloro-crotonaldehyde the alpha-chloro-beta-ethylacroleine there is obtained the Bz-3-ethylbenzanthrone.

2. A mixture of 16 parts of alpha-bromo-crotonaldehyde (obtainable according to German patent specification No. 559,329) and 100 parts of glacial acetic acid is added, drop by drop, within the course of 1 hour to a solution of 19.4 parts of anthrone in 300 parts of sulfuric acid of 80 per cent strength while cooling with ice. The solution assumes a dark red coloration whereas a vivid evolution of hydrogen bromide can be observed. The reaction is brought to an end and the product obtained with a quantitative yield is worked up as indicated in Example 1. It is identical with the benzanthrone derivative obtained according to Example 1.

3. 14 parts of alpha-chloro-beta-methoxybutyraldehyde (obtainable by the addition of methanol to alpha-chloro-crotonaldehyde and boiling under a pressure of 10 mm mercury at 48° C. to 50° C.) are condensed with anthrone and worked up as described in Example 1. The benzanthrone derivative thus obtained with a quantitative yield is identical with that of Example 1.

4. 13 parts of alpha-chloro-beta-hydroxybutyraldehyde (obtainable by the addition of hypochlorous acid to the crotonaldehyde according to German patent specification No. 559,329) are condensed as indicated in Example 1 with 19.4 parts of anthrone and worked up as described in that example. The condensation product thus obtained with a quantitative yield is the Bz-3-methylbenzanthrone melting at 113° C. to 114° C. named in Example 1.

5. 13 parts of acroleindichloride (obtainable by the addition of chlorine to acrolein, cf. Moureau, Ann. Chim. (9), 15, page 158) are caused to react with anthrone as described in Example 1.

6. From the crude product there is removed a small quantity of anthraquinone by extracting with a hot alkaline hydrosulfite solution. The product obtained with a nearly quantitative yield is unsubstituted benzanthrone free from chlorine and melts at 172° C.

6. 22.8 parts of 2-chloro-9-anthrone are treated in 300 parts of sulfuric acid of about 80 per cent. strength, as described in Example 1, with 10.5 parts of alpha-chloro-crotonaldehyde. There is obtained the 6-chloro-Bz-3-methylbenzanthrone recrystallizing from toluene in the form of yellow leaflets and melting at 180° C. to 182° C. It dissolves in concentrated sulfuric acid to an orange-red solution having a yellow-red fluorescence. The crude yield is quantitative.

Analysis:

Found: C=76.68 and 76.76
H= 3.66 3.71
Cl=13.71 13.80

Calculated: C=77.56
H= 3.98
Cl=12.74

7. By using for the condensation according to Example 1 instead of anthrone 21 parts of 1-hydroxy-9-anthrone, a hydroxy-Bz-3-methylbenzanthrone in which the hydroxy-group probably stands in 5-position is obtained with a quantitative yield and melts at 183.5° C. to 184.5° C. It may be recrystallized from acetone in the form of brown-yellow coarse needles. It dissolves in concentrated sulfuric acid to a yellow solution having a yellow-green fluorescence.

Analysis:

Found: C=82.74
H= 4.67
Calculated: C=83.05
H= 4.65

8. By substituting for the anthrone used in Example 1 25.4 parts of 3,4-dimethoxy-9-anthrone there is obtained with a quantitative yield, after saponification of the reaction product, the 7,8-dihydroxy-Bz-3-methylbenzanthrone melting at 218° C. to 220° C., which recrystallizes from methanol in the form of brown-yellow leaflets. The new benzanthrone derivative dissolves in dilute alkali and in concentrated sulfuric acid to a red solution.

9. By using for the reaction according to Example 1 instead of anthrone 22.4 parts of 4-methoxy-9-anthrone the 8-methoxy Bz-3-methylbenzanthrone is obtained with a quantitative yield which crystallizes from glacial acetic acid in the form of brown-yellow needles and melts at 120° C. to 122° C. It dissolves in concentrated sulfuric acid to a blue-red solution having a reddish fluorescence.

10. By using for the reaction according to Example 1 instead of the anthrone 22.5 parts of 1-hydroxy-4-methyl-9-anthrone, the 5-hydroxy-8-methyl-Bz-3-methylbenzanthrone is obtained with a quantitative yield which crystallizes from acetone in the form of yellow needles and melts at 198° C. to 200° C. It dissolves in concentrated sulfuric acid to a yellow solution having a green fluorescence.

11. By replacing in Example 1 the anthrone by 22.7 parts of 1,8-dihydroxy-9-anthrone, the 4,5-dihydroxy-Bz-3-methylbenzanthrone is obtained with a quantitative yield. It crystallizes from glacial acetic acid in the form of red needles and melts at 248° C. It dissolves in concentrated sulfuric acid to an orange-red solution having a yellow-red fluorescence.

12. By using for the reaction according to Example 1 instead of the anthrone 22.7 parts of 1,5-dihydroxy-9-anthrone there is obtained a 4,8-dihydroxy-Bz-3-methylbenzanthrone with a quantitative yield which crystallizes from glacial

acetic acid in the form of yellow-brown needles and melts at 262° C. to 263° C. It dissolves in concentrated sulfuric acid to a yellow-red solution having a green fluorescence and in dilute alkali to an orange-yellow solution.

13. 10.5 parts of alpha-chloro-crotonaldehyde are added, drop by drop, at room temperature to a solution of 23.8 parts of 9-anthrone-2-carboxylic acid (obtainable by reduction of benzophenone-2,4'-dicarboxylic acid and subsequent ring closure according to Limpricht, Annalen 309, 115 and 121, cf. also German patent specification No. 254,023) in 600 parts of sulfuric acid of 90 per cent. strength. The reaction is brought to an end by stirring for a prolonged time first at room temperature and finally at a raised temperature as described in Example 1. The Bz-3-methylbenzanthrone-6-carboxylic acid obtained with a quantitative yield is purified by dissolving it in dilute ammonia, boiling with animal charcoal and precipitating by means of acid. Recrystallized from chlorobenzene or nitrobenzene it forms a yellow powder of coarse small crystals, sintering at 286° C. and melting at 288° C. to 289° C. In dilute sodium carbonate solution the acid dissolves readily to a yellow solution and in concentrated sulfuric acid to a light yellow solution having a green-yellow fluorescence.

14. 18.2 parts of alpha-chloro-beta-methoxybutyraldehyde-dimethylacetal which is obtainable by introducing chlorine into a mixture of crotonaldehyde and methanol and boils under a pressure of 10 mm. mercury at 48° C. to 50° C., are condensed with anthrone and worked up as described in Example 1. The benzanthrone derivative obtained is identical with that obtained according to Example 1. The yield of the pure recrystallized product amounts to 60 per cent. of the theoretical.

We claim:

1. The process which comprises adding, while stirring, to a solution in sulfuric acid of a compound of the group consisting of 9-anthrone and 9-anthranoles which are unsubstituted in at least one of their positions peri to the 10-position a compound of the group consisting of those of the general formulae

and

and the aldehydeoacetals thereof, wherein R represents a member of the group consisting of hydrogen and alkyl and X represents a member of the group consisting of hydroxyl, methoxyl and halogen.

2. The process which comprises adding, while stirring, to a solution in sulfuric acid of a compound of the group consisting of 9-anthrone and 9-anthranoles which are unsubstituted in at least one of their positions peri to the 10-position a compound of the general formula

wherein R represents a member of the group consisting of hydrogen and alkyl.

3. The process which comprises adding, while stirring, at a temperature between 0° C. and room temperature to a solution in sulfuric acid of a compound of the group consisting of 9-anthrones and 9-anthranoles which are unsubstituted in at least one of their positions peri to the 10-position a compound of the general formula

4. The process which comprises adding, while stirring, at about room temperature alpha-chloro-croton-aldehyde to a solution in sulfuric acid of a compound of the group consisting of 9-anthrones and 9-anthranoles which are unsubstituted in at least one of their positions peri to the 10-position.

5. The process which comprises dropping, while stirring, at about room temperature alpha-chloro-croton-aldehyde into a solution of 9-anthrone in sulfuric acid of 80 per cent. strength.

6. The process which comprises dropping, while stirring, at about room temperature alpha-chloro-croton-aldehyde into a solution of 2-chloro-9-anthrone in sulfuric acid of 80 per cent. strength.

7. The process which comprises dropping, while stirring, at about room temperature alpha-chloro-croton-aldehyde into a solution of 9-anthrone-2-carboxylic acid in sulfuric acid of 80 per cent. strength.

8. Bz-3-methyl-6-chlorobenzanthrone melting at 180° C. to 182° C. and dissolving in concentrated sulfuric acid to an orange-red solution having a yellow-red fluorescence.
